UNITED STATES PATENT OFFICE.

WILLIAM K. FRALEY, OF LEBANON, ASSIGNOR OF ONE-HALF TO ROBERT SILVER, OF INDIANAPOLIS, INDIANA.

VEHICLE.

SPECIFICATION forming part of Letters Patent No. 357,956, dated February 15, 1887.

Application filed July 29, 1886. Serial No. 209,392. (No model.)

To all whom it may concern:

Be it known that I, WILLIAM K. FRALEY, of the city of Lebanon, county of Boone, and State of Indiana, have invented certain new 5 and useful Improvements in Vehicles, of which the following is a specification.

My said invention relates to that class of vehicles the bodies of which are supported by springs; and it consists, principally, in providing bars or levers which extend from the side bars or frame-work of the running-gear to the center, and are there so connected as to prevent the usual rocking or swaying of the body.

15 It further consists in the combination of such parts with a central spring connected thereto, in the manner hereinafter more particularly described and claimed.

Referring to the accompanying drawings, 20 which are made a part hereof, and on which similar letters of reference indicate similar parts, Figure 1 is a front elevation of a buggy-body provided with my improvements, the side bars being cut in section to show the levers and 25 spring more clearly; Fig. 2, a central vertical section through the spring and the immediate adjacent parts on the dotted lines 2 2 in Figs. 3 and 4, on an enlarged scale; Fig. 3, a transverse vertical section of the same on the dotted line 3 3 in Fig. 2, and Fig. 4 a transverse vertical section through the clips in which the levers are fulcrumed on the dotted line 4 4 in Fig. 2.

In said drawings the portions marked A 35 represent the body of the vehicle; B, a bar secured thereto, which forms the base or frame for the spring; C, said spring; D, the side bars or frame-work of the running-gear, and E the levers connected to said side bars mounted 40 upon pivots or fulcrums connected to the bar B, and connected at the inner ends to the spring.

The vehicle-body A is any ordinary body or upper portion of a vehicle.

45 The bar B is a straight plain piece of timber secured to the under side of said body. Where a spring of the style illustrated is used, it has a central opening large enough to receive all but the outer coil of said spring, and at each 50 side of said opening there is preferably a slot through which the bolts securing the clips (in

which the levers are fulcrumed) pass, and thus said clips and levers are rendered adjustable, as will be hereinafter more fully described.

The spring C is shown as a coiled spring, 55 but may be any spring desired, although I regard a coiled spring as the best for my purpose. It is secured to the bar B by bolts e, and a bolt, C', having a bifurcated lower end, is secured to its central coil. 60

The side bars or frame-work, D, are or may be of any ordinary or desired construction. Clips d are secured thereto, to which the ends of the levers E are attached.

The levers E are pivoted or fulcrumed in 65 clips E', which are secured to the bar B by bolts e', passing through slots therein, as shown most plainly in Figs. 2 and 4. They are secured, as before stated, to clips d on the side bars or frame-work D, by means of pivots or 70 bolts d'. Their inner ends are slotted, and said slots pass over a pivot-bolt, c', which passes through the bifurcated lower end of the bolt C'. These slots not only permit the 75 desired freedom of motion of the body and the spring, but permit the parts to be longitudinally adjusted so that the fulcrums may be nearer to or farther from the pivot-bolt c', and thus the power of the spring increased or decreased, as will be readily understood, and also 80 to permit the device to be applied to vehicles where the side bars are different distances apart. As will be observed, these levers not only serve as a means of utilizing the spring force of the spring C, but also as stays or 85 braces to prevent lateral movement or rocking of the vehicle-body, they being attached both to the frame-work of the running-gear and to the bar B, which is secured to said body. This object could not well be accomplished without 90 the slots in the inner ends of said levers, and therefore said slots are important as a feature of my invention.

I am aware that vehicles have heretofore been 95 constructed with levers fulcrumed on parts secured to the under side of the body, and having one end connected to the axles or side bars and the other end to the body, or a spring at its center, and I therefore do not claim the construction broadly, but limit myself to the particular 100 construction and arrangement of parts herein shown, and set forth in the claims.

Having thus fully described my said invention, what I claim as new, and desire to secure by Letters Patent, is—

1. In a vehicle, the combination of the body 5 A, bar B, secured thereto, spring C, mounted in an opening in said bar, the side bars, D, and levers E, fulcrumed in the clips E', said clips E' secured to said bar B, one end of said levers being attached to said side bars, and their other ends to being formed slotted and mounted on the bolt c' in the lower end of the bolt C', and said bolt C' secured to the spring C, substantially as set forth.
2. The combination, in a vehicle, of the body 15 A, bar B, secured on the under side of said body transversely thereof, the spring C, mounted in a central opening in said bar, and having a bifurcated bolt, C', secured to its center and ex-

tending down therefrom, the side bars, D, and levers E, fulcrumed in the clips E', adjustably mounted on the under side of said bar B, one end of said levers being attached to said bars, and their other ends being each formed with a longitudinal slot and mounted on the transverse bolt c' in the lower end of the bifurcated bolt C', whereby said levers are adapted to slide to permit the sway of the body, and also to permit the adjustment of the fulcrums, as herein shown and described.

In witness whereof I have hereunto set my 30 hand and seal, at Indianapolis, Indiana, this 24th day of July, A. D. 1886.

WM. K. FRALEY. [L. S.]
